UNITED STATES PATENT OFFICE

93,771

DESIGN FOR A SPECTACLE FRONT

George P. Kimmel, Washington, D. C.

Application October 31, 1932, Serial No. 45,668

Term of patent 14 years

To all whom it may concern:

Be it known that I, GEORGE P. KIMMEL, a citizen of the United States, residing at Washington, District of Columbia, have invented a new, original, and ornamental Design for a Spectacle Front, of which the following is a specification, reference being had to the accompanying drawing, forming a part hereof.

Figure 1 is a front elevation of a spectacle front, showing my new design.

Figure 2 is a top edge view thereof.

The feature of the design is in the combination of the particular lens shape shown, in association with high-mounted end pieces, and a

nose bridge with sides which conform in outline to the configuration of the inside edges of the lenses, being in substantial parallelism therewith, and a bridging element conforming generally in configuration to the curvature of the top edges of said lenses and being so shaped and arranged as to harmonize and present a substantially continuous flowing line with said top edges of the lenses.

I claim:

The ornamental design for a spectacle front, as shown and described.

GEORGE P. KIMMEL.
